UNITED STATES PATENT OFFICE.

FRANK MOSSBERG, OF ATTLEBORO, MASSACHUSETTS, ASSIGNOR TO FRANK MOSSBERG COMPANY, A CORPORATION OF RHODE ISLAND.

LOOM-BEAM.

1,004,584.

Specification of Letters Patent.

Patented Oct. 3, 1911.

Application filed November 1, 1910. Serial No. 580,221.

To all whom it may concern:

Be it known that I, FRANK MOSSBERG, a citizen of the United States, residing at Attleboro, in the county of Bristol and State 5 of Massachusetts, have invented certain new and useful Improvements in Loom-Beams, of which the following is a specification.

My invention relates to loom beams and is particularly purposed to facilitate the 10 mounting and dismounting of the heads, to adapt the heads to firm attachment to the beam body regardless of variations in dimensions of the particular body receiving the same, and to effect these ends in a simple, 15 strong, and inexpensive structure.

To the above ends essentially my invention consists in such novel construction, combination and arrangement of parts as are embraced in the appended claims.

20 In the accompanying drawings which form a part of this specification, Figure 1, is a side elevation of my novel loom beam, Fig. 2, a front elevation of the same, and Fig. 3, a central vertical section of the same, 25 and Fig. 4, a section on line $\alpha\alpha$ of Fig. 2.

Like reference characters indicate like parts throughout the views.

My loom beam in its present embodiment comprises the usual body 1, which may be 30 either solid or hollow according as the material is of wood or metal. Upon this are mounted heads which are identical in detail, so that a description of one will suffice for both.

35 Each head 2, is provided with a peripheral flange 3, in this case a rolled flange; and has a central aperture, the edge of which is extended to form a flange or hub 4, provided with openings 5, through which loosely pass 40 blocks 7, having preferably enlarged outer portions 8, provided with longitudinal slots 9, in their outer faces. The bottom faces, 10, of the blocks are concaved to conform to the surface of the body against which they abut.

45 For strengthening purposes the head is provided with radially disposed hollow ribs 12.

An annular disk or clamping ring 13, mounted upon the hub 4, has upon its inner 50 margin oblong inclined cavities 14, of greater length than the blocks, adapted to receive the enlarged portions of the latter. The inclined edges 15, of the disk at the margins of the cavities rest in the slots 9. The periphery of the disk is provided with teeth

17, engaging a worm 18, upon a rod 19, journaled in ears 20, fixed by rivets 22, to the head. The end of the rod is squared as at 23 to accommodate a wrench.

In order to insure against accidental transverse movement of the disk under the influence of the worm, brackets 25, each provided with a slot 26 to loosely receive the margin of the disk, are fixed by rivets 28 to the body near opposite ends of the worm. 60 There may be one or more of these brackets. 65

In applying or clamping the heads to the body, the rods 19, are turned to rotate the disks 13, whereby the blocks 7, are gradually forced inwardly against the body. 70

What I claim is:—

1. In a loom beam, the combination with the body and heads, the latter being formed with integral flanges upon their central portions constituting hubs around the body, 75 said flanges having openings, clamping blocks upon the hubs extending through said openings, said hubs forming seats for the operative parts, and means surrounding and movable on said flange for inwardly forcing said blocks.

2. In a loom beam, the combination with the body and heads, the latter being formed with hubs having openings, clamping blocks mounted upon the hubs and extending through said openings, and rotary means surrounding and movable on said flange for simultaneously inwardly forcing said blocks toward the body. 85

3. In a loom beam, the combination with the body and heads, of hubs upon the heads provided with openings, clamping blocks slidably mounted in the openings, rotatable clamping disks sleeved upon the hubs and engaging the blocks, and means surrounding and movable on said flange for rotating the disks. 90

4. In a loom beam, the combination with the body and heads, of hubs upon the heads embracing the body, clamping blocks upon the hubs, and clamping disks sleeved upon the hubs and provided with inclined bearing faces engaging the blocks and means positively engaging said disks to rotate them and simultaneously operate said clamping 100 blocks against the body.

5. In a loom beam, the combination with the body and heads, of hubs upon the heads engaging the body and provided with openings, blocks resting upon the hubs and ra- 110

dially movable in the openings and provided with slots, clamping disks sleeved upon the hubs and provided with inclined marginal bearing faces seated in the slots, and means 5 positively engaged with and constructed for rotating the disks to force the blocks against said body.

6. In a loom beam, the combination with the body and heads, of hubs upon the heads 10 engaging the body and provided with openings, clamping disks surrounding the hubs and provided with inclined cavities, blocks radially movable in the openings and extending into the cavities in contact with 15 the disks and means positively engaged with the outer periphery of said disks for rotating the latter.

7. In a loom beam, the combination with the body and heads, of flanges upon the 20 heads constituting hubs around the body, clamping blocks upon the hubs in contact with the body, clamping disks rotatably mounted upon the hubs in contact with the blocks provided with teeth, worms carried 25 by the heads engaging the teeth, and members upon the head loosely engaging the disks.

8. In a loom beam, and combination with the body and heads, of flanges upon the

heads constituting hubs around the body, 30 clamping blocks upon the hubs in contact with the body, clamping disks rotatably mounted upon the hubs in contact with the blocks provided with teeth, and worms carried by the heads engaging the teeth.

9. In a loom beam, the combination with a body and heads, the latter having flanges 35 constituting hubs, of clamping blocks upon said hubs in contact with the body and means rotatably sleeved about said hubs and having cam portions coöperating with cam portions on said blocks for simultaneously actuating all of said blocks.

10. In a loom beam, a body, heads having flanges constituting hubs around said body 40 and having openings, clamping blocks upon said hubs working through said openings, and means rotatably mounted upon and surrounding said hubs and having cam portions cooperating with cam portions on said blocks and contacting with said blocks for simultaneously actuating the latter.

In testimony whereof I have affixed my signature in presence of two witnesses.

FRANK MOSSBERG.
